UNITED STATES PATENT OFFICE.

EDUARD THEISEN, OF MUNICH, GERMANY.

GAS-PURIFIER.

No. 895,313.

Specification of Letters Patent. Patented Aug. 4, 1908.

Application filed October 25, 1904. Serial No. 229,925.

To all whom it may concern:

Be it known that I, EDUARD THEISEN, engineer, citizen of Germany, residing at Munich, Bavaria, Germany, have invented certain new and useful Improvements in Gas-Purifiers; and I do hereby declare the following to be a full, clear, and exact description of the invention, such as will enable others skilled in the art to which it appertains to make and use the same:

This invention relates to apparatus for the treatment of liquids and gases for evaporating, cooling, heating, absorbing, purifying and the like objects.

Forms of apparatus for this purpose have heretofore been used consisting essentially of a drum provided with longitudinally extending ribs and a casing surrounding said drum and ribs, the gas passing through the space between the drum and casing from one end to the other and the liquid passing through said space in the opposite general direction. In practice, the ribs have been given a more or less inclined direction upon the outer walls of the drum so as to cause a spiral travel of the liquid in contact with and under the influence of the gas pressure supplemented by its centrifugal pressure.

In the forms of apparatus hitherto known, it has not been possible to regulate the capacity for treatment of the apparatus or the velocity or quantity of the fluids passing therethrough, except by taking the apparatus apart to alter the inclination of the ribs or to insert another drum having ribs arranged with greater or less obliquity.

The object of this invention is to provide an apparatus of this general character which is subject to regulation with facility and without expense, this object being attained by providing the inner face of the casing surrounding the drum with inclined channels or passages which, under the influence of the gas pressure upon the liquid, will cause the liquid to travel in a spiral path of greater or less inclination independent of the inclination of the ribs upon the drum.

With this object in view, the invention resides in the structural features hereinafter more elaborately described and particularly set forth in the claims.

For purposes of illustration, a preferred embodiment of the invention with certain modifications is set out in the accompanying drawings, in which:

Figure 1 is a vertical longitudinal section

through an apparatus embodying the invention; Fig. 2 represents different forms of guiding surfaces upon the inner side of the casing; Figs. 3, 4 and 5 are fragments showing the construction of the guiding channels; Fig. 6 shows the arrangement of one form of guiding channels on the inner wall of the casing; and Fig. 7 is a transverse section through the drum and casing showing the relation of the ribs and guiding channels.

Referring to the drawings more in detail, *a* represents passages or channels arranged helically upon the inner wall of the casing *a'* and extending progressively from the smaller 70 to the larger end of the conical casing.

b indicates the ribs or flanges extending longitudinally of and upon the outer wall of the drum *b'* mounted to rotate within the casing *a'* upon the shaft *c*. Into the space between the drum and casing, gas is introduced at *d* and finds its exit at *e*, while water or other suitable liquid is introduced into the same space at a point not shown near the gas exit and finds its outlet from the opposite end 80 at *f*. The ribs *b* may be arranged either parallel to the axis of the drum or they may be arranged at a slight inclination thereto.

The spiral channels arranged upon the inner wall of the casing may be formed in any 85 suitable manner, but in order to facilitate the removal of guiding channels with a certain inclination and their substitution by channels having a different inclination, in order to regulate the operation of the apparatus, a removable guiding surface is provided.

In Figs. 3, 4 and 5 are shown one form of arrangement consisting of a wire netting composed of rods *g* extending substantially 95 parallel to each other and cross wires *h* intersecting the rods *g* and interwoven therewith to form a netting. The rods *g* and wires *h* may be of the same size, but preferably they are of different sizes as shown. They may occupy a position very nearly at right angles to each other as shown in Fig. 3, in which case, the channels upon the inner wall of the casing *a'* are inclined but slightly and the travel of the liquid through the apparatus 100 will be slow, or the rods *g* and the wires *h* may have a greater inclination as shown in Figs. 4 and 5, in which event, the netting when applied to the inner face of the casing will present channels having a greater inclination and the flow will be correspondingly rapid from the water inlet to the outlet.

The inner surface lining of the casing, formed as hereinbefore described, may be readily inserted and removed, thus rendering it practicable to have several interchangeable linings and possible, by the mere act of substitution, to regulate the operation of the apparatus with great nicety. The regulation may be further effected by a mere shifting or displacing of the parallel rods *g* within 5 the casing so as to increase or diminish their inclination. Not only may the guiding channels *a* formed between the rods *g* be arranged at greater or less inclination, but the depth may also be made to vary by the use 10 of rods *g* of different sizes, or if the channels are formed in the wall of the casing itself, they may be made of greater or less depth so that the water in passing through the space between the drum and casing will not only 15 travel in a spiral direction through the channels, but will also flow over the ridges separating the same and thus be given a riffling effect. This effect is also produced by the cross wires *h* over which the water must 20 flow when traveling in the channels.

Having thus described my invention, what I claim as new and desire to secure by Letters Patent, is:

1. In an apparatus of the character described, the combination with a rotary drum provided with exterior longitudinal ribs, of a casing surrounding said drum and provided upon its inner surface with ridges forming helical channels.

2. In an apparatus of the character described, the combination, with a rotary drum provided with exterior longitudinal ribs, of a casing surrounding said drum and provided upon its inner surface with adjustable ridges 35 forming helical channels.

3. In an apparatus of the character described, the combination, with a rotary drum provided with exterior longitudinal ribs, of a casing surrounding said drum and provided 40 upon its inner face with ridges forming helical channels and with cross ridges of less height.

4. In an apparatus of the character described, the combination, with a rotary drum provided with exterior longitudinal ribs, of a 45 casing surrounding said drum, and a wire

netting arranged upon the inner surface of the casing with its wires extending in a helical direction.

5. In an apparatus of the character described, the combination, with a rotary drum 55 provided with exterior longitudinal ribs, of a casing surrounding said drum, and a wire netting displaceably arranged upon the inner face of the casing with its wires extending in a helical direction.

6. In an apparatus of the character described, the combination, with a rotary drum provided with exterior longitudinal ribs, of a casing surrounding the drum, and a wire netting arranged upon the inner face of the casing and composed of cross wires of diverse sizes, the larger wires extending in the helical direction.

7. In an apparatus of the character described, the combination, with a rotary drum 70 provided with exterior longitudinal ribs, of a casing surrounding the drum, and a wire netting arranged upon the inner face of the casing and composed of wires of diverse sizes loosely interwoven, the larger wires extending in a helical direction and displaceable to vary the inclination to the axis of the drum.

8. In an apparatus of the character described, the combination, with a rotary drum provided with exterior longitudinal ribs, of a 80 casing surrounding said drum, and a wire netting removably arranged upon the inner surface of the casing with its wires extending in a helical direction.

9. In an apparatus of the character described, the combination, with a rotary drum provided with exterior longitudinal ribs, of a casing surrounding the drum, and a wire netting removably arranged upon the inner face of the casing and composed of wires of diverse sizes loosely interwoven, the larger wires extending in a helical direction and displaceable to vary the inclination to the axis of the drum.

In testimony whereof I hereunto affix my signature in the presence of two witnesses.

EDUARD THEISEN.
